UNITED STATES PATENT OFFICE.

JOSEPH MEINECKE, OF PAIA MAUI, TERRITORY OF HAWAII, ASSIGNOR OF ONE-HALF
TO W. A. RAMSAY, OF HONOLULU, TERRITORY OF HAWAII.

INTERMEDIATE CARRIER FOR CANE-SUGAR MILLS.

Application filed March 23, 1922, Serial No. 546,195. Renewed March 19, 1924.

To all whom it may concern:

Be it known that I, JOSEPH MEINECKE, a citizen of the United States, and a resident of Paia Maui, Territory of Hawaii, have 5 invented certain new and useful Improvements in Intermediate Carriers for Cane-Sugar Mills, of which the following is a specification.

My invention relates to improvements in 10 cane sugar mills, and it consists in the constructions, combinations and mode of operation herein described and claimed.

An object of the invention is to provide 15 an improved intermediate carrier or cane chute for transferring the bagasse from one macerating mill to another.

A further object of the invention is to provide an intermediate carrier which is widened at the summit to facilitate the passage 20 of the bagasse across.

Other objects and advantages will appear in the following specification, reference being had to the accompanying drawings, in which:

25 Fig. 1 is a plan view illustrating the widened intermediate carrier,

Fig. 2 is a side elevation of the intermediate carrier, and

Fig. 3 is a detail cross section on the line 30 3—3 of Fig. 2.

This invention is an improvement on the cane sugar mill disclosed in my Patent 1,401,095, granted December 20, 1921. The purpose of both inventions is to provide a 35 carrier for conveying bagasse from one sugar cane macerating mill to another. The carrier consists of a chute through which the bagasse is pushed from one mill to the other. The chute is of such a construction 40 that no injury can result thereto from the great pressure under which the bagasse is discharged from one of the mills.

The old construction disclosed in the patent referred to and repeated here for the 45 purpose of illustration, comprises the chute generally designated 13. This chute includes a bottom plate 14 disposed at an angle of from 30 to 45 degrees (preferably 45 degrees) from the horizontal, and another 50 bottom plate 15 which is disposed preferably at an angle of from 30 to 45 degrees from the horizontal, eliminating all moving parts so that there can be no delay due to the breakage of chain slats, etc. The bottom 55 plate (of which 14 and 15 are parts) bends

at the summit 9 which must be crossed by the bagasse upon being discharged by the mill 11 on its way to the mill 12.

The intake side 15 of the chute 13 has scrapers 22 which engage the expressing 60 rollers of the mill 11 so as to remove any of the substance which would otherwise adhere to the surfaces and be carried around. The intake or receiving side 15 is of less inclination than the discharge side 14. In 65 other words, the latter (14), is steeper than the former (15). The steepness of the discharge side 14 facilitates the expulsion of the mass of bagasse after it crosses the summit 9. Bars 23 carry plates to which the scrapers 70 22 are attached. Each of the scraper bars has a lever 20 at each end. Rods 21 with turn buckles are attached to the ends of the levers and to fixed parts of the frame. The turnbuckles are turned to set the scrapers 75 22 in respect to the expressing rolls in the mill 11.

The receiving end of the chute 13 has a cover 25. This cover may extend as far 80 toward the summit as conditions may require. The cover is hinged at 24 so that it may be lifted. It carries clips 26 at the free end to rest on the edges of the chute sides. Other details of construction of the chute, such as the side plates at the receiving 85 and discharge ends, bracing means, etc., need not be described here, since they have no direct bearing on the improvement, which resides wholly in the middle chute structure. Fig. 1 shows the chute 13 to have been 90 widened at 27 across the summit 9. In other words, the widest part of the chute is across the ridge or summit. From this point, the sides converge or taper until they assume the normal width at the mills 11 95 and 12.

The walls or sides of the chute slant outwardly or diverge at 28. The widening of the chute at the summit in the manner described has been found to cause a more efficient operation than the straight-sided chute of the co-pending application.

Pipes 30, perforated underneath, sprinkle 100 the bagasse with water as it passes the summit 9. The water aids maceration. Obviously, the widened chute summit lengthens 105 the sprinkling area. A better penetration of the bagasse by the water is secured because of the thinning of the strata of bagasse when crossing the summit. This thinning of 110

the bagasse strata is caused by the spreading of the mass when it reaches the widened zone 27.

The bagasse is ejected from the mill 11 at 5 a given speed. The mass moves up the incline 15 at a given speed. Obviously, the rate of movement of the mass diminishes as the chute widens toward the summit 9 and this slackening of the speed of the mass is 10 an additional aid to the penetration thereof by the water from the pipes 30.

I claim:—

1. An intermediate feed chute for sugar mills comprising oppositely inclined portions laterally widening toward the summit 15 to cause a spreading and thinning of a bagasse mass moving up one incline.
2. In combination with adjacent sugar cane mills, a chute between the two embodying 20 a gradually widening portion for reducing the depth and rate of movement of a bagasse mass discharged by one mill.
3. A chute to be disposed between adjacent mills, having portions inclining from 25 and widening laterally toward a summit.
4. A chute to be disposed between adjacent mills, comprising a bottom plate inclining from and widening laterally toward a summit, and side plates inclining outwardly.
- 30 5. The combination of a pipe for dis-

charging macerating fluid, and a chute including portions inclining to a summit substantially beneath the pipe, and laterally widening toward said summit to cause a reduction of the depth and rate of motion of a bagasse mass moving toward said summit and thereby secure a more thorough penetration of the bagasse by said fluid.

6. An intermediate feed chute comprising 35 oppositely sloping bottom portions disposed at different inclinations and widening toward a summit, side walls flaring upwardly, and a cover for one portion of the chute, hingedly mounted and carrying means to 40 rest on the edges of adjacent sides.

7. In combination with adjacent sugar cane mills, a chute extending from one to the other, the ends of the chute corresponding in width to the length of the rolls of 50 the mills but laterally wider at the middle portion of the chute than at its ends.

8. In combination with adjacent sugar cane mills, a chute extending from one to the other including inclined portions united 55 at the summit, the ends of the chute corresponding in width to the length of the rolls of the mills, the inclined portions gradually widening laterally until the place of union at the summit is reached.

JOSEPH MEINECKE.
